J. C. FARLEY

ADJUSTABLE DOOR FASTENING DEVICE

Filed Oct. 13, 1926

UNITED STATES PATENT OFFICE.

JOHN C. FARLEY, OF OPELIKA, ALABAMA.

ADJUSTABLE DOOR-FASTENING DEVICE.

Application filed October 13, 1926. Serial No. 141,323.

This invention relates to improvements in adjustable door fastening devices, particularly adapted for use in connection with refrigerator doors or the like.

- 5 An object of this invention is to provide a door fastening device which may be adjusted in order to obtain an efficient closing effect of the door in relation to the refrigerator box or otherwise.
- 10 Another object of this invention is to provide in a door fastening device resilient means for closing the door with any desired degree of force depending upon the amount of potential energy in the resilient member 15 and the degree to which the potential energy of the resilient member has been subjected by means of a suitable wing nut or otherwise.

A further object of this invention is to 20 provide a door fastening device in which the ordinary wearing effect on the different parts will be eliminated, at the same time will function to produce an efficient closure effect.

A further object of this invention is to 25 provide a door fastening device comprising a minimum number of elements, a means for securely combining these elements together in order to form an efficient and inexpensive door fastener in which the different parts 30 will cooperate without loss of efficiency due to the frictional wearing between the elements, a disadvantage which is a common occurrence in the fastening devices of the type now in use, particularly in connection 35 with refrigerators and other like devices.

Other objects of this invention will appear in the following detailed description of the device and as disclosed in the single sheet of drawings which is herewith made a part 40 of this application.

In the drawings Fig. 1 illustrates a vertical sectional view of the door fastening device, disclosing the elements in released assembled relationship.

45 Fig. 2 represents a sectional elevational view of the fastening device in latched position.

Fig. 3 illustrates a sectional view of Fig. 1, taken along line 3—3.

50 Fig. 4 represents a sectional view of Fig. 3, taken along line 4—4.

Fig. 5 illustrates a perspective view of the fastening device in interlocked relationship.

55 Fig. 6 illustrates a perspective view of the

portion of the fastening device, disclosing a modification of this invention pertaining to a contact element.

Numeral 1 designates a container such as a refrigerator box or otherwise, adapted to have attached thereto a door 2 of the type common to ice boxes or refrigerators. Fastened to the door 2 in a suitable location is a bracket element 3 adapted to have pivoted or otherwise connected thereto a cam portion 4 either integrally connected or detachably connected to an operating handle 5. The cam 4 and operating handle 5 may be pivotally attached to the bracket 3 by means of a pivot pin 6 or otherwise.

Suitably fastened to the refrigerator box 1 or other form of container is a base plate 7, which may be fastened to the box 1 by means of fastening elements 8. Extending from and suitably fastened within the base plate 7 are guide members 9, and a spindle 10. The guide members 9 are adapted to extend through openings in a suitably formed grooved keeper portion 11, the spindle being adapted to extend downwardly from the keeper element 11 a suitable distance in order to allow for a wing nut 12 to cooperate with the spindle at this outer end, the outer end of the spindle 10 and the wing nut to be properly threaded. The keeper element 11 is provided with a hollow portion 13 of sufficient capacity to allow for the movement therein of a resilient tension device 14 in the form of a spring device. The base of the spring tension device 14 will 80 function to rest on a shoulder 15 formed integrally from the keeper element 11 at the base of the opening 13, the outer end of the opening 13 will be formed to allow freedom 85 of movement to the wing nut 12.

Extending from the keeper element 11 is a suitably formed lug 16 which is adapted to cooperate with the cam element 4 in such a manner that when the operating handle 5 is brought downward, the cam 4 will cooperate 90 with the lug 16 in such a manner as to force the keeper element 11 and the tension spring 14 rearwardly to an extent as disclosed at 17 depending upon the amount of tension placed upon the spring by the wing nut 12, thereby functioning to produce a firm and efficient closure between the door and the refrigerator box.

Fig. 6 illustrates a modification of this invention, particularly in the form of the

cam element, which may be integrally a part of the operating handle 5 or a detachably connected roller member 18, which may be rotatively connected to the handle portion 5 by means of pivoting pins 19.

In operation this invention provides a door fastening means which may be adjusted for various degrees of force between the door and container or refrigerator box. 10 When it is desired to interlock or fasten the elements together, it is merely necessary to operate the handle 5 in the usual manner and adjust the wing nut 12 for the desired degree of power or pressure to be exerted 15 against the door for closure purposes.

While specific embodiments of this invention are shown herein, it is to be understood that changes and alterations may be made by those skilled in the art without departing from the scope of the invention as defined herein.

What I claim is:

1. A keeper construction for maintaining a door and container in close relationship 25 under tension, consisting of a plurality of sections, one section being fixed to the container, the other sections being adjustably connected to the fixed section, a counterbore in one of the adjustably connected sections, a 30 resilient member in the counterbore, and adjustable means for bringing the resilient member under tension between the fixed section and the adjustably connected section.
2. A keeper construction for maintaining 35 a door and container in close relationship under tension, consisting of a plurality of sections, one section being fixed to the container, the other sections being adjustably connected to the fixed section, a counterbore 40 in one of the adjustably connected sections, a resilient member in the counterbore, and adjustable means for bringing the resilient member under tension between the fixed section and the adjustably connected section, 45 the counterbored section having a suitable

latch lug extending therefrom for cooperating with a door element.

3. A keeper construction for maintaining a door and container in close relationship under tension, consisting of a plurality of 50 sections, one section being fixed to the container, the other sections being adjustably connected to the fixed section, a counterbore in one of the adjustably connected sections, a resilient member in the counterbore, and 55 adjustable means for bringing the resilient member under tension between the fixed section and the adjustably connected section, the counterbored section having a suitable latch lug extending therefrom for cooperating 60 with a door element, the tension means comprising a coil spring within the counterbore slidably mounted on a spindle.

4. A keeper construction for maintaining a door and container in close relationship 65 under tension, consisting of a plurality of sections, one section being fixed to the container, the other section being adjustably connected to the fixed section, a counterbore 70 in one of the adjustably connected sections, a resilient member in the counterbore, and adjustable means for bringing the resilient member under tension between the fixed section and the adjustably connected section, the counterbored section having a suitable 75 latch lug extending therefrom for cooperating with a door element, the tension means comprising a coil spring within the counterbore slidably mounted on a spindle, one end of which extends in interlocked relationship 80 with the fixed section, the other end being threaded for receiving a tension adjusting element adapted for varying the tension 85 on the resilient member thereby functioning to maintain a close relationship between the latch lug and the cooperating element on the door.

In testimony whereof I affix my signature.

JOHN C. FARLEY.
